Primary Examiner—Louis S. Zarfas*Assistant Examiner*—G. Andoll[57] **CLAIM**

The ornamental design for a menstrual cycle tracking apparatus, as shown.

DESCRIPTION

FIG. 1 is a front view of the menstrual cycle tracking apparatus of the present invention;

FIG. 2 is a rear view of the menstrual cycle tracking apparatus of FIG. 1;

FIG. 3 is a right side view of the menstrual cycle tracking apparatus of FIG. 1;

FIG. 4 is a left side view of the menstrual cycle tracking apparatus of FIG. 1;

FIG. 5 is a top view of the menstrual cycle tracking apparatus of FIG. 1;

FIG. 6 is a bottom view of the menstrual cycle tracking apparatus of FIG. 1; and,

FIG. 7 is a top, front, right side perspective view of the menstrual cycle tracking apparatus of FIG. 1.
